US00D594871S

(12) **United States Design Patent**
Ma

(10) **Patent No.:** **US D594,871 S**
(45) **Date of Patent:** **** Jun. 23, 2009**

(54) **FLASH DRIVE**

(76) Inventor: **Tien-Chi Ma**, No. 75, Sec. 2, Minquan E. Rd., Zhongshan District, Taipei City (TW)

(**) Term: **14 Years**

(21) Appl. No.: **29/309,359**

(22) Filed: **Jul. 31, 2008**

(51) **LOC (9) Cl.** 14-99

(52) **U.S. Cl.** **D14/480.6**

(58) **Field of Classification Search** D14/301, D14/313, 348-358, 363, 368, 370, 432-436, D14/496, 136-137, 155-156, 167-168, 240, D14/242, 299, 411, 384-385, 518, 402; D3/201, D3/273; D13/149, 184; 710/300-301; 439/131, 439/140-142; 361/684-686; 360/97.01
